SEWING MACHINE LUBRICATION

John D. Karle, Roselle Park, N. J., assignor to
 The Singer Manufacturing Company, Elizabeth, N. J., a corporation of New Jersey

Application September 11, 1945, Serial No. 615,511

4 Claims. (Cl. 112—256)

1

This invention relates to sewing machines and more particularly to means for lubricating the rotary take-up of a sewing machine.

One of the primary objects of this invention is to provide means for automatically supplying oil from a reservoir to a bearing of a rotary take-up while the machine is operating, and to return excess oil thrown off by the take-up bearing to the reservoir, thereby creating a closed circulatory system for the oil.

Another object of this invention is to provide oil-collecting guards for the take-up and other actuating mechanism within the hollow-head and to return the oil collected by the oil guards to the hollow-arm of the machine frame.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is an enlarged vertical sectional view taken through the head and bracket-arm of a sewing machine embodying my invention.

Fig. 2 is a head end elevation with a part of the take-up mechanism broken away to show some of the parts in section.

Fig. 3 is a top plan view of the machine shown in Fig. 1, the cover-plate of the bracket-arm being removed to expose the operating mechanism beneath.

Figs. 4 and 5 are sectional views taken substantially along the lines 4—4 and 5—5 of Fig. 3, and including the cover-plate.

In its embodiment selected for illustration, my invention is shown as applied to the rotary take-up of the lock-stitch sewing machine disclosed in my Patent No. 2,332,087 dated October 19, 1943.

As shown, the machine has a frame including a bracket-arm 10 terminating in a hollow-head 11. Journaled in the bearings 12 and 13 in the bracket-arm is a needle-bar actuating shaft 14. Fixed to the end of the shaft 14 which extends into the hollow-head 11 is a crank-disk 15 carrying a crank-pin 16 which is embraced by an apertured boss 17 on one end of a needle-bar link 18;

2

the other end of the link being operatively connected with the vertically reciprocating needle-bar 19 by the pivot-stud 20. The needle-bar 19 is journaled in spaced bearings 21, 22 and carries an eye-pointed needle 23 which is adapted to cooperate with a loop-taker (not shown) in the formation of stitches.

The rotary take-up mechanism comprises a spiral gear 24 fixed to the shaft 14 and meshing with a second spiral gear 25 fixed to one end of a tubular shaft 26 which extends through and is journaled in a bearing 27 carried by the bracket-arm 10 of the machine. The shaft 26 extends through the hollow-head 11 and through a ball-bearing 28 carried by a cover-plate 29 which is secured to the hollow-head 11. The plate 29 is formed with an aperture through which the shaft 26 extends and around the aperture the plate 29 extends forwardly forming a sleeve-like portion 30 which is embraced by a sun-gear 31 fixed by a screw 32 to the plate 29. From the above it will be understood that the shaft 26 extends through the stationary sun-gear 31 and is adapted to be rotated by the needle-bar shaft 14 relative thereto.

Fixed to the end of the shaft 26 and rotatable therewith is a disk 34 carrying a sleeve bearing 35 in which is journaled the hub 36 of a small disk 37. The hub 36 is embraced by a metal insert 38 of a fiber planet gear 39 which meshes with the stationary sun-gear 31. The ratio of these gears is as 1 is to 1. It will be understood that the gear 39, hub 36 and disk 37 rotate as a unit in the bearing 35 and are rigidly clamped in assembled relationship by a bolt 40 which extends through the hub of the disk and has its threaded end received by a nut 41 which is fixed to the gear 39. Carried by the small disk 37, at a distance from its axis of rotation, is a thread-engaging stud 42 which supports a guard-disk 44. The large disk 34 carries a thread-engaging element 45 (Fig. 2) which supports an outer guard-disk 45'. The above described mechanism is fully shown and described in my prior Patent No. 2,332,087, previously referred to, to which reference may be had for a more detailed disclosure.

When the machine is operating, oil is supplied under pressure through the conduit 46 to the bore 47 in the needle-bar shaft 14. In order to supply oil to the bearing surface between the

sleeve 35 and hub 36, I have provided a radial duct 48 which extends through the wall of the shaft 14 and through the gear 24. Oil is thrown through the duct 48 onto the gear 25, from whence it is thrown by centrifugal force against the scroll shaped wall 49 which depends from a cover-plate 50 secured to the top of the arm 10 by the screws 51. The oil when it strikes the wall 49 is projected forwardly into a reservoir or oil-collecting trough 52 milled in the arm 11. The trough 52 has a bottom wall to provide a low spot from which the oil is led through a duct 53 formed in the depending portion 43 of the upper wall of the arm 10. Carried by the depending wall portion 43 and communicating with the duct 53 is a stationary tube 54 which extends through the bore 55 in the shaft 26 in spaced relation to the shaft. A radial duct 56 connects the bore 55 in the shaft 26 with the bushing 35 which is recessed to receive a pad 57 and a wick 58 of fibrous material. From the above, it will be understood that the oil thrown off by the gear 25 will be collected in the trough 52 and flow by gravity from the trough through the conduit 53, tube 54 and duct 56 to the pad 57 and wick 58 which bears against the hub 36 of the disk 37 and lubricates it. While the pad 57 and wick 58 act as metering devices, some excess oil reaches the bearing and is thrown off by centrifugal force. In order to catch the excess oil, I have formed the plate 29 with a circular groove 60 which encircles the disk 34, and the disk 34 is formed with an oil sling 61. The groove 60 provides a sump 62 in which the excess oil collects. Extending from the sump 62 is a conduit 63 which passes through the hollow-head and extends into a stationary tube 64 which is carried by the partition-wall 65 of the hollow-head 10. From the above, it will be obvious that the oil is supplied from the hollow bracket-arm to the bearing of the rotary take-up and the excess oil thrown off by the bearing is collected and returned to the hollow bracket-arm, thereby forming a closed circuit for the oil. It will be understood that the oil in the reservoir 52 will flow by gravity through the conduit 53 and tube 54, and the excess oil will flow along the bore of the tubular shaft back into the hollow bracket-arm. In short, the tube 54 delivers an over-abundance of oil to the duct 56 and the excess is returned to the bracket-arm cavity through the bore 55 of the shaft 26.

Oil is also supplied through the bore 47 of the shaft 14 and the duct 59 to the bearing of the crank-pin 16. In order to catch any surplus oil thrown off by the crank-pin, I have secured a circularly shaped guard 66 to the end of the shaft 14 by a screw 67. The guard 66 is arranged to catch the oil which is thrown off by centrifugal action from the crank-pin bearing. When the machine is stopped and the needle-bar moved to its raised position, as shown in Fig. 1, the oil will flow from the guard 66 through a tube 68. The tube 68 passes through the crank-disk 15 and overhangs a milled groove 69 formed in the bearing bushing 12. The oil delivered to the groove 69 by the tube 68 flows through the conduit 70 and back into the hollow bracket-arm.

Also, oil flows through the radial duct 71 into a chamber 72 which is packed with wicking; the oil supplied to this chamber flowing through suitable openings (not shown) in the bearing bushing 27 to the bearing surface between the shaft 26 and sleeve bearing 27. In order to prevent excess oil from escaping along the shaft 26 and into the hollow-head 11 the shaft 26 is

formed with a spiral oil groove 74 which terminates in a radial duct 75 in the shaft 26. When the machine is operating, the spiral groove 74 causes the oil to travel along the shaft 26 and forces it through the radial duct 75 into the bore 55 of the shaft 26, the oil being discharged through the end of the shaft into the hollow bracket-arm.

Having thus set forth the nature of the invention, what I claim herein is:

1. A take-up for sewing machines having a hollow bracket-arm comprising, a tubular shaft, gears for rotating said shaft, a take-up disk carried by said shaft and having a bearing to be lubricated, means for constantly feeding oil under pressure to the working faces of said gears, a removable cover-plate located above said gears and having an oil deflecting wall, a trough formed in the bracket-arm and adapted to receive oil thrown from said gears and deflected by said wall, conduits for conducting the oil from said trough into the bore of the tubular shaft, and a radial conduit for conducting the oil from said shaft bore to said bearing.
2. A take-up for sewing machines having a hollow bracket-arm, comprising a tubular shaft, gears for rotating said shaft, a take-up disk carried by said shaft and having a bearing to be lubricated, means for feeding oil under pressure to said gears, a trough formed in the bracket-arm and adapted to receive oil thrown from said gears, conduits for conducting the oil from said trough into the bore of the tubular shaft, a radially arranged conduit intersecting the bore of the shaft for conducting oil to said bearing, and a plate formed with a groove which encircles said take-up disk for collecting excess oil thrown off by said bearing and means for returning the oil by gravity to the hollow bracket-arm.
3. A sewing machine having in combination, a hollow bracket-arm, a needle-bar shaft journaled in said arm, a take-up shaft journaled in said arm, gearing connecting said shafts, means for supplying oil under pressure to said gears, a reservoir formed in said arm, a removable cover-plate overlying said gears and formed with a depending curved portion which is adapted to deflect oil thrown by said gears into said reservoir, a rotary take-up actuated by said take-up shaft and having a bearing, means for conducting oil from said reservoir to said bearing, and means encircling said take-up for collecting excess oil thrown from said bearing and returning it by gravity to the interior of the bracket-arm.
4. A sewing machine having in combination, a hollow bracket-arm, a needle-bar shaft journaled in said arm and formed with a longitudinal bore, a tubular rotary take-up actuating shaft journaled in said arm, gearing connecting said shafts, means for supplying oil under pressure through the bore in said needle-bar shaft and including a radial duct in one of said gears for conducting the oil to the working faces of said gears, a reservoir formed in said bracket-arm above the level of said take-up actuating shaft, a cover-plate overlying said gears and formed with a curved portion arranged to deflect oil thrown off by said gears into said reservoir, a tube carried by said bracket-arm and extending into said take-up actuating shaft, said tube being connected to said reservoir by a conduit formed in the bracket-arm, a rotary take-up disk actuated by said shaft and carrying a bearing located at a distance from the center of said disk, and a

radial conduit formed in said disk for supplying oil from said tubular shaft to said bearing.
